DEVICE FOR PUNCTURING CONTAINERS
AND DISPENSING FLUID HELD UNDER
PRESSURE IN SAID CONTAINERS

Lyle M. Cooper, Rahway, N. J., assignor to Standard Oil Development Company, a corporation of Delaware

Application September 19, 1946, Serial No. 697,939

2 Claims. (Cl. 222—82)

1

The present invention relates to a device for dispensing fluids. More particularly it relates to a device for dispensing fluids held under pressure in a sealed container.

It is an object of the invention to provide a comparatively simple dispensing device providing both a valve mechanism and perforating means which will permit connection of the dispensing device to a pressurized container for fluids without appreciable loss of pressure or contents during such operation, and which will permit controlled discharge of the container contents without substantial leakage. It is also an object of the invention to provide a convenient stand and holder for the container during use, and between periods of such use.

The invention and its objects are fully set forth in the following specification and the accompanying drawings, in which:

Fig. 1 is a side elevation, partly in vertical section through one form of the device, including a fluid container.

Fig. 2 is a vertical section through the valve structure and a fluid container along the line II—II of Fig. 1, and

Fig. 3 is a side elevation, partly in vertical section through an alternate form of the device.

Referring specifically to the drawings, the numeral 1 denotes a holder-stand in which is contained a valve mechanism, including a hollow valve body 2, having a threaded nipple 3 extending upwardly from one end thereof, and preferably integral therewith. The nipple 3 is of less diameter than the body 2, thus forming a shoulder 2a at the base of the nipple. The nipple 3 is provided with a substantially conical perforator-tip 3a having a sharply pointed end. An annular washer 4 is supported on the shoulder 2a. A passageway 3b opens outwardly through the tip 3a, at one end, and extends into communication with the interior of the valve body 2 at the other. If desired, the tip may be provided with a concave recess at one side through which the passageway 3b may open.

The container 5 may be of any suitable form or construction, but when for use in combination with the holder-stand illustrated in Fig. 1, should have a concave head 5a to which is secured centrally an annular, interiorly threaded bushing 6, adapted for threaded engagement by the nipple 3 of valve body 2, thereby accomplishing perforation of the container head 5a by means of the perforator-tip 3a of nipple 3. Complete engagement of the nipple and bushing brings the bushing into pressure and fluid-tight relation with

the washer 4, sealing the junction of the container and the valve body.

In order that the nipple 3 may adequately engage the bushing 6 before perforation of the head 5a by the perforator-tip 3a, it is essential that the depth of the bushing 6 be slightly greater than the length of the perforator-tip 3a. For example, if the perforator-tip 3a is $\frac{1}{16}$ inch long, the bushing should be at least $\frac{1}{4}$ inch in depth. Thus the nipple 3 may be brought into threaded engagement with the bushing before contact between the tip and the container head is positively established.

In the form of the invention illustrated by Figs. 1 and 2, a valve seat 2b is formed at the upper end of the hollow space in the valve body 2 at the junction of the passageway 3b therewith. The hollow space within the valve body 2 opens outwardly at the lower end.

Within the body 2 a spring actuated valve assembly is provided. A stopper valve member 7, held in a cup-shaped head 8 normally engages the valve seat 2b. Preferably the stopper 7 is of a resilient material such as rubber, either synthetic or natural, and may be held in place by inwardly crimped portions of the head as at 7a. A helical valve spring 9 is disposed below the head 8, held under compression between the head 8 and an annular spring seat 10 which in turn bears against an annular seal 11, the entire assembly being retained within the body 2 by means of the screw-slotted, annular retainer member 12 provided for threaded engagement with the inner wall of the valve body. A valve stem 13 having an enlarged portion or button 13a at its outer end extends through the retainer, seal, seat and spring into rigid connection with the head 8. The stem 13 is long enough to extend downwardly beyond the valve body.

To withdraw the stopper valve 7 from engagement against the seat 2b, the valve stem 13 is drawn downwardly by means of a trigger 14 acting against the button 13a. The trigger is arcuately shaped, being provided with a slotted portion 14a adapted to receive the extended portion of valve stem 13 and engage the button 13a at the lower end of the stem.

The trigger 14 is provided with upwardly flanged edges 14b rounded at the upper ends for engagement with the lower end of the valve body 2, and is pivotally supported with relation to the body 2 by means of a substantially C-shaped swivel mount 15 engaging opposite sides of the body 2, as by insertion of the opposed end portions of element 15 into prepared openings or

depressions in the body 2, and by the button 13a on valve stem 13.

Providing for discharge of fluid from the container 5 through the valve body 2 is a discharge conduit 16, including a nozzle member 16a at its outer end. The nozzle 16a may be integrally formed, or, as illustrated, a separate element sweated, press fitted, or threaded into or around the conduit. The inner end of the conduit opens through a lateral orifice through the valve body into the hollow space therein at a point below the valve seat 2b.

In the form of the invention illustrated in Fig. 3, a different type of holder stand is illustrated, adapted to receive a different type of container. As shown, the holder 1 is provided with a separate standportion 1a. Other modifications of construction and operation are to be observed, but the basic elements of the device according to the invention are to be found in all forms illustrated. It is to be noted also that each of the two types of containers, the two types of holder-stands, and the two types of valves illustrated may be interchanged or recombined as desired. For example, the valve as illustrated in Figs. 1 and 2 may be substituted for the valve illustrated in Fig. 3 and vice versa. Likewise by suitable modification of the conformation of the upper surface of the respective holders, the containers of Figs. 1 and 3 may be substituted one for another.

In the device as shown in Fig. 3, the hollow valve body 2 is provided with a laterally disposed chamber, opening rearwardly of the body through an opening in which is disposed an annular seal 17, and forwardly of the body through a restricted opening formed by an annular shoulder 18 against which is disposed an annular seal 19. The passageway 3b extends angularly through the nipple 3 and tip 3a communicating with the valve chamber at its lower end. A distributor ring 20, forming the fixed element of a sliding valve assembly is located substantially centrally of the valve chamber, between the two annular seal members, 17 and 19. The distributor member 20 may be of any convenient form which will provide an annular space between the chamber wall and the member, and afford close sliding contact interiorly with a movable discharge tube 21. As shown, the member 20 is in one piece, having ports 20a opening through the member 20, into the annular space around it.

The discharge tube 21 is of a length slightly greater than that of the upper portion of the holder-stand 1, and extends through a passageway formed in the stand concentrically with the chamber of valve body 2. This passageway is enlarged stepwise, at its rearward end to receive an annular retainer member 22 having a flanged end 22a providing an annular seat for the helical valve actuating spring 23. An enlarged operating button 24 closing the rearward end of the discharge tube 21 provides a bearing surface for the outer end of the spring 23. The spring 23 is held under slight compression between the retainer flange 22a and the button 24 by means of a flanged nozzle tip 25 for the forward end of the tube 21, the flanged portion of the tip 25 engaging the surface of the holder-stand 1.

One or more valve ports 21a are provided in the tube 21 preferably by drilling the tube and deforming inwardly the edges of the drilled opening. The ports 21a should be spaced from the forward end of the tube at a distance slight-

ly greater than that from the forward end of the stand passageway to the rearward end of the chamber in valve body 2. Likewise, the limit of movement of the valve tube through the chamber of valve body 2 should be less than the front to back dimension of the valve body. For example, if the distance from the forward end of the stand passageway to the rearward end of the chamber in valve body 2 is 2½ inches, the distance of the port or ports 21a from the forward end of tube 21 should be approximately 2 $\frac{1}{32}$ inches. Also, if the front to back dimension of the valve body 2 is $\frac{1}{2}$ inch, the limit of movement of the valve tube through the chamber of valve body 2 should be about $\frac{3}{8}$ inch.

In using the dispensing device illustrated, and described above, the container 5 is attached to the holder-stand 1 by means of the threaded nipple 3 on valve body 2, and the threaded bushing 56 on the container. By means of the container, the bushing 6 is threaded on the nipple 3 until a tight seal is made between the bushing and washer 4. At that point, the perforator-tip 3a will have ruptured the container head 5a permitting passage of fluid into the passageway 3b.

In the form of the device illustrated in Figs. 1 and 2, rearward pressure against the trigger 14 withdraws the stopper valve 7 from its seat 2b permitting fluid to flow through the passageway 3b and the valve chamber into the discharge tube 16 and outward through nozzle 16a. When pressure on the trigger is released, the actuating spring 9 will reseat the valve 7 against the pressure of fluid in the container, shutting off the flow of fluid from the nozzle 16a.

In the form of the device illustrated by Fig. 3, forward pressure against the operating button 24 will move the discharge tube 21 forward through the distributor ring 20 and the passageway in the stand 1 to a point where port or ports 21a open into the space formed by the distributor ring 20, or into apposition with the ports 20a, permitting fluid to flow through the passageway 3b and the valve chamber into the discharge tube 21 and outward through nozzle 25. When pressure on the button 24 is released, the actuating spring 23 will withdraw the discharge tube 21 from its extended position, and thereby the port or ports 21a from access to the space within the distributor ring 20, or apposition with ports 20a, shutting off the flow of fluid through the discharge tube 21 and nozzle 25.

Although the invention has been described with reference to its preferred embodiments, it is to be understood that various modifications and alternate arrangements are possible without departing from the inventive concept disclosed. It is not intended that the invention shall be limited by such specific description or illustration provided for the purpose of disclosure, but only by the appended claims.

I claim:

1. A fluid dispensing valve comprising a valve body, a lateral chamber in said body opening through the side walls thereof, a threaded nipple at one end of said body, said nipple terminating in a substantially conical perforator-tip, a passageway extending through said nipple, opening at one end through said tip, and communicating at the other end with the valve chamber, a distributor ring member within said chamber, held in fluid-tight relation to the chamber walls immediately below the opening of the nipple passageway into the chamber, a spring actuated

conduit valve member, having a discharge nozzle at one end extending concentrically through said valve chamber and ring member in slidale, fluid-tight relation thereto, at least one orifice in the wall of said conduit valve member, disposed in space relation to the nozzle end thereof, and normally sealed from communication with said nipple passageway, and means closing the other end of said conduit valve member adapted to receive pressure as required to move said conduit valve member through said valve chamber and distributor ring member, whereby an orifice in the conduit member wall is brought into communication with the nipple passageway through said distributor ring.

2. A fluid dispensing valve, comprising a valve body, a threaded perforator nipple at one end of said body, a lateral passageway through said body and a longitudinal passageway through said nipple opening, at its inner end, into the lateral passageway, a conduit valve member, having a discharge nozzle, extending through said lateral passageway for reciprocal movement therein, in fluid tight relation to said passageway and normally closing the inner end of the nipple pas-
